ILLINOIS.

SUCTION-VALVE HOLDER.

1,229,459.

Specification of Letters Patent. Patented June 12, 1917.

Application filed October 9, 1915. Serial No. 55,106.

To all whom it may concern:

Be it known that we, FRANKLIN G. HOBART and CHARLES B. JAHNKE, citizens of the United States, residing at Beloit, in the 5 county of Rock and State of Wisconsin, have invented a certain new and useful Improvement in Suction-Valve Holders, of which the following is a specification.

The valves of gas engines, air compressors and other machines provided with automatic suction valves controlling the inlet sometimes make a chattering noise due to the fact that the springs when of proper tension for controlling the valves allow the 15 valve when first opened to rebound and strike the seat. The rapid repetition of this action when the gas is entering causes this objectionable chattering.

The object of this invention is to provide 20 a supplementary means readily applicable to devices of this character which does away with the chattering.

The invention consists in means for carrying out these objects, which can be easily 25 and cheaply made and installed, satisfactorily operated and not readily liable to get out of order. It also consists in features and details of construction which will be hereafter more fully described and claimed 30 as the specification proceeds.

Referring to the drawings, in which similar numerals indicate the same parts throughout the several views,

Figure 1 is a side view of mechanism illustrating this invention.

Fig. 2 is taken on the line 2 of Fig. 1.

Fig. 3 is a front,

Fig. 4 is a side, and

Fig. 5 is a bottom detail view of the supplemental spring removed from the rest of the mechanism.

The drawings show walls 10, 11 and 12 of a chamber or passageway 14 of an engine through which the gas or fluid to be controlled passes. In the construction well known in the art, the wall 11 is provided with a port 16 closed by valve 18 having a spindle 20 slidable through lugs 22 and 24 on opposite sides of wall 10. Through the lower 45 end of the spindle 20 is a pin 26 or other securing device against which the collar 28 takes bearing. Between collar 28 and the wall 10 surrounding the lug 24 is a compression spring 30 which serves to hold the

valve 18 upon its seat. On valves automatically opened by the suction this spring 30 is made light to offer little resistance to opening. When the valve is suddenly opened by the suction, a vibrating action is set up, the valve striking its seat at each movement and causing this chattering noise. In order to obviate this difficulty, a supplemental spring device is provided consisting, in the form shown, of a pair of flat springs 32 and 34, having their ends bearing on 55 the cylindrical surface 36 of the collar 28. These springs introduce a frictional resistance on the valve 18 which prevents the chattering but does not interfere with its operation. 70

In the specific embodiment shown in the drawings, these springs 32 and 34 are made integral with a supporting plate 38 having through it a perforation 40 of sufficient size to fit loosely over the lug 24 so that the body 75 of this plate 38 is engaged by the upper end of spring 30 to press it against wall 10 to consequently hold or support the springs 32 and 34 in proper relation with the entire device, the springs being held central by 80 the collar 36 on the valve stem 20.

In the operation of the device, when a suction is created above the valve 18, the valve is opened against the force of spring 30, the surface 36 of collar 28 sliding under 85 the frictional resistance springs 32 and 34.

Having thus described our invention, what we claim as new and desire to secure by Letters Patent, is:—

1. In a device of the class described, a 90 machine casing, a valve having a seat therein, a valve stem extending from said valve, a compression spring engaging a collar on the valve stem and bearing against a portion of the case, and a supplemental spring 95 mechanism bearing on the sides of said collar to retard the movement of the valve stem, for the purpose set forth.

2. In a device of the class described, a 100 case having a port or passageway therein to be closed, a valve closing said port, a valve stem extending from said valve, a compression spring engaging a collar on the valve stem and bearing against a portion of the engine case, a supplemental spring mechanism mounted on a plate interposed between the compression spring and the case having members engaging the sides of said collar 105

on the valve stem to retard the movement thereof, for the purposes set forth.

3. In a device of the class described, a valve having a spring urging it against its seat, and another spring arranged to positively apply frictional resistance to the movement of said valve.

4. In a device of the class described, a valve, a valve seat, a spring urging the valve to its seat, and a spring device arranged to apply a frictional resistance to the movement of the valve.

5. In a device of the class described, a valve, a valve seat, a spring urging the valve to its seat, and a spring device arranged to apply a frictional resistance to the movement of the valve, said valve seating spring reacting against the device to hold the latter in place.

20 6. In a device of the class described, a valve, a valve seat, a spring urging the valve to its seat, and a second spring co-operating with the valve to apply a friction resistance to the movement of the valve.

25 7. In a device of the class described, a valve, a valve seat, a spring urging the valve to its seat, and a second spring coact-

ing directly with the valve to apply a frictional resistance to the movement thereof.

8. In a device of the class described, a valve, a valve seat, a spring urging the valve to its seat, and a spring device fixed relatively to the valve and arranged to apply a frictional resistance to the movement of said valve.

35 9. In a device of the class described, a valve, a valve seat, a spring urging the valve to its seat, means for guiding the valve in its movement to and from its seat, and means for applying a frictional resistance to the movement of the valve, said means acting to produce a frictional force in excess of that incident to a normal guiding engagement between a part of the valve and a surface of the guiding means.

40 In witness whereof we have hereunto subscribed our names in the presence of two witnesses.

FRANKLIN G. HOBART.
CHARLES B. JAHNKE.
